UNITED STATES PATENT OFFICE.

CHRISTY BROWN, OF WILMETTE, ILLINOIS, ASSIGNOR TO AMERICAN CAR ROOF COMPANY, OF CHICAGO, ILLINOIS, A CORPORATION OF ILLINOIS.

CAR-ROOF.

1,218,624.

Specification of Letters Patent. Patented Mar. 13, 1917.

Application filed August 9, 1915. Serial No. 44,433.

To all whom it may concern:

Be it known that I, CHRISTY BROWN, a citizen of the United States, residing at Wilmette, in the county of Cook and State of Illinois, have invented certain new and useful Improvements in Car-Roofs, of which the following is a specification.

Heretofore, to compensate for or permit the unavoidable weaving, twisting and warping of railway car-bodies, without damage or injury to the sheet-metal roofs, it has been customary to make the roofs so-called flexible, that is, the parts thereof have been so associated with one another as to permit a certain amount of play or relative movement between them, such parts, however, being rigidly or unyieldingly fastened to the car-body side and end walls. In some instances, the roof elements have been unyieldingly secured together, as by direct riveting, and rigidly fastened to the car-body, dependence being placed upon the inherent flexibility of the roof members themselves to prevent injury during the distortions of the car-body.

Neither of these plans has proved entirely satisfactory in actual railroad service and, in endeavoring to overcome their salient defects, I have discovered that, although, at first thought it is not feasible to loosely or adjustably connect the roof to the car-body, this can, nevertheless, be satisfactorily accomplished, regardless of whether the roof itself is flexible or its parts fixedly secured to each other.

My invention, therefore, concerns improvements along this line, particularly in the way of attaching the roof to the body, and also pertains to certain features of novelty and advantage in the roof structure itself.

In order that those skilled in the art may have a full understanding of the invention, I have illustrated a preferred embodiment of the same in the accompanying drawings forming a part of this specification, and to which reference should be had in connection with the following detailed description.

In these drawings, throughout the various views of which like reference characters refer to the same parts,

Figure 1 is a fragmentary side elevation of a railway freight car, equipped with the improved form of roof.

Fig. 2 is a central, longitudinal, vertical

section, through the structure shown in Fig. 1.

Fig. 3 is a fragmentary, end view of the construction illustrated in Fig. 1.

Fig. 4 is a partial, vertical cross-section through the upper portion of the car-body and roof.

Fig. 5 is a perspective view of one of the braces or brackets which secures the ends of the carlines to the car-body side walls.

Fig. 6 is a fragmentary, vertical section through the roof, between carlines.

Fig. 7 is a fragmentary section, showing the parts in Fig. 6, and at right angles to the view of Fig. 6; and

Fig. 8 is a partial, vertical cross-section, through the center of one of the carlines and its associated cap strip.

Referring to the drawings, it will be observed that the car-body has the usual side and end walls 10 and 11, respectively, the former being provided with posts 12 and at its top having a longitudinal Z-bar 13, with an inwardly extended flange 14, a vertical web 15, and a lower, outwardly projecting flange 16. The end wall also has its posts 17 capped with a Z-bar end-plate 18, having an inwardly extended top flange 19 and an outwardly-projecting bottom flange 20.

The roof frame may or may not have a ridge-pole, but in the particular embodiment of the invention presented in these drawings no such pole is used. A suitable number of cambered, channel carlines 21 are used, these being spaced apart the desired distance and each having projecting from the opposite edges of its trough-shaped portion the outstanding flanges 22, 22. As is clearly illustrated, these carlines are disposed with their troughs upwardly, and at each end each has

fastened thereto a pressed, sheet-metal brace or bracket 23, illustrated in perspective in Fig. 5. Each of these brackets comprises a base-plate portion 24 having at its outer edge a marginal, depending flange 25, an upwardly bent trough-shaped portion 26 projecting inwardly, as shown in the various figures. This part 26 is provided with tapered side wings 27, merging into apertured flanges 28, which, by means of rivets 29, are fastened to the carline flanges 22, the body portion of the carline being snugly received in the depression or socket 26, its flanges resting on flanges 28, as shown. In this way, the carline has one of its braces or brackets

rigidly and immovably fastened to each of its ends. The base portion 24 of each bracket is supplied with two or more elongated apertures 29 having their longer axes disposed transversely of the bracket, that is, longitudinally of the car side when the bracket is in place. Each of these brackets or braces is fastened to the inwardly projecting flange 14 of the longitudinal Z-bar 18 by means of bolts 30 accommodated in holes in flange 14 and in the brace apertures 29, the diameters of such bolts being less than the width of the holes 29, so that these braces and their carlines and the car-body side walls are free to shift relatively to one another, with a capability of movement lengthwise of the car greater than that crosswise of the car-body. To permit this possibility of relative movement, the parts 24 of the braces project beyond the webs of the Z-bars 13, as is clearly illustrated in Fig. 6, so that the flange 25 is spaced outwardly away from the outer face of such web.

As is shown in Fig. 6, the ends 31 of the carlines 21, including their outstanding flanges, are curved or bent downwardly beyond their association with the channels 26 of the brackets.

Positioned between such downwardly curved ends of the carlines and the top faces of the parts 24 of the brackets, and extended the full length of the car, I employ eave or weather strips 32 of general Z-shape in cross-section, and secured to the protruding portions of the brackets by rivets 33 received in suitably spaced holes through the web of the eave strip and in holes 34 of the brackets.

As indicated in Fig. 6, the web of the eave strip rests directly on the top faces of the brackets, with its outer, depending flange against the outer faces of such brackets, its inner, inclined flange being readily accommodated between the carlines and braces, as shown.

Between adjacent carlines, and with their end portions bearing against the side walls of such carlines and accommodated beneath the curved carline flanges, I employ wooden filler strips 35 of the shape in cross-section shown in Fig. 6, which are interposed between the end portions of the carlines and the eave strip, as illustrated.

The curved, sheet-metal roof-plates 36 extend transversely across the car from side wall to side wall and extend lengthwise of the car-body from carline to carline, the opposite edges of such plates having downturned flanges 37, accommodated in the troughs of the carlines and bearing against the inner faces of the side walls of such carlines, as indicated in Fig. 7. As the sides of the car, these roof-plates, including their flanges 37, are bent or curved downwardly 65 to follow the contour of the corresponding

parts of the carlines, the roof plates terminating, as is shown in Fig. 6, at the top of the eave strip 32 and flush with the outer face of the depending flange of the latter.

Channel cap or weather strips 38 are employed and fit snugly in the channels of the carlines, holding the roof-plate flanges 37 firmly between their side walls and the walls of the carlines. As is clearly illustrated in Fig. 7, the roof-plates rest directly on the carline flanges, and the outstanding, oppositely-extended flanges 39 of the cap strips rest, in turn, upon the top faces of the roof-plates. This construction provides two superposed troughs, that of the carline and that of its cap strip. The ends of such cap strips follow the contour of the bent, terminal portions of the carlines and roof-plates, and end in downwardly extended ears 40, held to the braces or brackets 23 by means of bolts 41 extended through holes in such ears and apertures 42 of the bracket flanges 25. Each of these holes 42 preferably has a side opening 43, so that the bolt may be slid in sidewise, as will be readily understood. In order that whatever moisture might possibly find access to the trough of the carline may be readily discharged over the eave or weather strip 32, the web 44 of the cap strip at each end is apertured, or cut away, at 45 for the drainage indicated.

At the ends of the car, the last roof-plate 46 has one edge accommodated in the adjacent carline in the manner depicted in Fig. 7. This plate rests upon the cambered or bent flange 19 of the end Z-bar or plate 18, and projects beyond the web of such bar in a downwardly curved portion 47, having a marginal flange 48 secured to the web of the part 18 by a number of bolts 49, which pass through holes in the web and through substantially horizontally-disposed, elongated slots 50 in the flange 48.

The bolt and slot connections 30, 29, of the braces or brackets to the Z-bars 13 permit the roof as a whole to shift lengthwise of the car-body, the curved or bent portions 47 of the end plates yielding sufficiently to permit such movement, that is the parts 47 will become distorted, more or less. The roof is also free to move sidewise of the car-body by reason of the connections 30, 29, and the end connections 49, 50. It will be apparent that the roof as a whole constitutes a unit, loosely or yieldingly connected to the car-body proper, that is to say, all of the elements of the roof are unyieldingly fastened together and depend upon the adjustment of the braces and of the end roof-plates for securing it to the car-body 125 side and end walls.

In case any portion of the car-body tends to settle or become depressed more than any other portion, the roof can readily accommodate itself to such distortions by reason 130

of the resiliency and flexibility of the roof-
plates themselves; that is to say, dependence
is placed upon the yielding capability
of the plates, rather than upon relative
5 movements of the elements constituting the
roof structure.

While I have herein illustrated, in de-
tail, and described somewhat minutely one
10 particular embodiment of this invention, it
is to be understood that the invention is not
limited or restricted to the precise and ex-
act structural features presented, because
these may be modified within comparatively
15 wide limits, without departure from the heart
of the invention and without the sacrifice of
any of the substantial benefits and advan-
tages thereof.

I claim:

1. In a railway-car, the combination of a
20 car-body, a car-roof including carlines,
sheet-metal roof-plates, and carline braces

substantially rigidly connected together
without capability of substantial bodily
movement relatively to one another, and
25 loose connections between said carline braces
and car-body permitting movement of the
roof relative to the car-body, substantially
as described.

2. A structure as specified in claim 1 in
combination with carline cap-strips rigidly
30 connected to said braces, substantially as de-
scribed.

3. A structure as specified in claim 2 in
which the braces are slotted in combination
35 with bolts accommodated in said slots and
securing the braces to the car-body, such
slots and bolts permitting the movement
specified between the roof and car-body, sub-
stantially as described.

CHRISTY BROWN.
